DESIGN FOR AN ANDIRON OR SIMILAR ARTICLE

Oscar P. Kurrle, Dearborn, Mich.

Application August 30, 1946, Serial No. 132,968

Term of patent 7 years

(Cl. D81—6)

To all whom it may concern:

Be it known that I, Oscar P. Kurrle, a citizen of the United States, residing at Dearborn, Wayne County, Michigan, have invented a new, original, and ornamental Design for an Andiron or Similar Article, of which the following is a specification, reference being had to the accompanying drawing, forming a part thereof, in which:

Fig. 1 is a front elevation showing an andiron or similar article embodying the present invention.

Fig. 2 is a top plan of the andiron shown in Fig. 1.

Fig. 3 is a section taken substantially on the line 3—3 in the direction of the arrows, Fig. 1.

The dominant features of the design reside in the portions shown in full lines.

I claim:

The ornamental design for an andiron or similar article, substantially as shown and described.

OSCAR P. KURRLE.
